TELEPHONE SYSTEM

Eduard Wochinger, Brieselang, near Berlin, Germany, assignor to "Fides" Gesellschaft für die Verwaltung und Verwertung von Gewerblichen Schutzrechten mit beschränkter Haftung, Berlin, Germany

Application August 5, 1938, Serial No. 223,208
In Germany August 17, 1937

9 Claims. (Cl. 179—7.1)

The present invention relates to a circuit arrangement of telephone systems in particular semi-automatic telephone systems with principal and sub-exchanges.

When in such exchanges the reckoning of the conversation fee in the principal exchange is carried out either automatically by devices in the exchange or by an operator, then with connections between the sub-exchange subscribers which do not extend to the main exchange it is difficult to convey the necessary data for the reckoning of the fees to the principal exchange.

The present invention concerns the determination of length of conversation in such systems and this is attained in that with connections between sub-exchange subscribers which do not extend over the principal exchange switch means become effective at certain time intervals under the influence of a time switch arranged in the connecting path, and send out information to a central set in the principal exchange over connections not included in the existing path.

The present invention attains special importance in semi-automatic telephone systems with small country centres, in which the connection between sub-exchange subscribers are made by an operator. An advantage of this system over known arrangements consists in that after the making of such a connection and removal of the plug by the operator all connecting devices and lines not completely necessary for the conversation are free and available for other connections, thus the operator is also completely cut off from the connection which she has just made.

The reckoning of the fees for such connections corresponding to the value is possible without any further means, since the operator can ascertain the distance, i. e., the zone from the number of the calling and of the called subscriber. The subject of the present invention now permits, in addition to a stepping off of the conversation, fees according to the duration of the conversation by transmitting time signals to the operator.

In the drawings an embodiment of the invention is shown. Fig. 1 is a trunking diagram for the five exchanges A, B, C, D and E, while Fig. 2 shows in detail the circuit arrangements in exchange C.

The principle of the invention can for example be used in systems with the network as shown in Fig. 1. Diagrammatically a small country centre is shown with the sub-exchange B, C, E and a principal exchange A, in which latter, is

the operator, by whose aid connections for semi-automatic traffic are made and supervised.

The principal exchange A with the operator's position is connected with the sub-exchange connecting lines L1, L2, L3. The connecting system VA in the principal exchange serves to make the connection with the operator over the connecting lines. In the operator's position there is a lamp board with the signal lamps Z1, Z2, Z3, Z4 which are switched in by impulses from a sender over one of the lines L1 to L3 and taken up by one of the receivers E1, E2, E3, E4 situated at the other end of this line.

The exchange B is assumed to be completely automatic. Subscribers who are connected to this exchange can therefore by means of an impulse series sent out from their selection dial, make the desired connection inside their own exchange without the help of the operator, and also make automatic connections with subscribers of other exchanges. Since in this automatic working the fee is determined in known manner with attention to the time by means of meters influenced by metering stepping on devices, in connections 15 which proceed from subscribers of the exchange and sending out of time signals to the operator is not necessary. From the exchange B a connecting line L5 also extends to the exchange D while over line L4 the exchange C, and from this exchange over the connecting line L6 the sub-exchange E, can be reached.

The particular operations should now be considered which are made to transfer the time signals by means of the different possible connections.

If, for example, a subscriber N2 of the exchange C wishes to make a connection with a subscriber of the automatic exchange B when the subscriber N2 lifts up his receiver and operates the crank, the call finder ASC is started up and sets itself on the calling subscriber. Over the transfer UEC and the secondary line switch MWC the connecting line L4 is reached. From here the call is passed on over the transfer UEB1 of the exchange B and the connecting link VAI to the connecting line L1 and to the connecting link VA in the principal exchange A. A call signal lies up in the operator's position in known manner so that she is informed of the presence of a call. She connects herself with the calling subscriber and makes an enquiry. The operator then makes the connection to the desired subscriber N1 of the exchange B so that the two subscribers are connected as follows: subscriber N2 of the said ex-

change C, call finder ASC, transferrer UEC, secondary line switch MWC, line L4, transferrer UEB1, group selector GW, line selector LW, subscriber N1, devices for determining the particulars of the conversation and for sending out data for the purpose of transferring a time signal are situated for this connection in the transferrer UEB1. Here in dependence on a time switch a release relay is energized which stimulates the sender S1 to send out the high frequency impulse over line L1 at definite times during the connection. The impulse is taken up by the receiver at the principal exchange A which brings about the connection of the corresponding signal line Z1. The operator has the conversation tickets to hand in a compartment by the lamp Z1, and can now draw up the conversation period and hence the value of the fee from the signal transmitted.

If an internal connection in the exchange C is required i. e., a subscriber N2 of this exchange wishes to speak with a subscriber N3 connected to the same exchange, then when the receiver at the calling set N2 has been lifted and the crank operated the same path is built up to the operator as in the first case. By the setting of the direction selector RWC in the exchange C and the line selector LWC by the sending out of determined impulse series by the operator the desired connection is then made. For sending out the time signal to the operator the time switch in the transferrer UEC now comes into effect. At definite time intervals it stimulates the sender in the exchange C and the high frequency impulse is now sent over the connecting line L4 and the loop b coupled with the connecting line L3. From the connecting line L3 the receiver E3 in the principal exchange A takes up the impulse and connects the corresponding signal lamp Z3. The operator can therefore register the conversation time for this connection on a ticket in the compartment situated by this lamp.

The coupling lead b as already mentioned connects the connecting line L4 with the connecting line L3. It is so constructed by the inclusion of frequency filters or the like that only the transmission of high frequency impulses is possible over this lead and not other switching operations so that disturbances by this lead in the connecting and speaking traffic are avoided with certainty. If the subscriber of the exchange C wants to make a connection with the subscriber N7 of the sub-exchange E the connecting path extends after the connection has been made by the operator from the subscriber N2 over the call finder ASC, transferrer UEC, direction selector RWC, connecting line L6, secondary line switch MWE, transferrer UEE, direction selector RWE, line selector LWE, subscriber N7. In the same way as for internal connections between two subscribers of the exchange C the time switch in the transferrer UEC now comes into effect for these connections and stimulates the sender S3 to send out high frequency impulses at definite time intervals. The transferring of the high frequency impulses results in the same manner as for interval connections between subscribers of the exchange C.

If a subscriber of the exchange C wishes to make a connection with a subscriber of the exchange D the connection extends after the setting of the different connecting devices by the operator as follows: subscriber N2, call finder ASC, transferrer UEC, secondary line switch MWC, connecting line L4, transferrer UEB1, 75

group selector GW, transferrer UEB2, connecting line L5, secondary line switch MWD of the sub-exchange D, transferrer UED, direction selector RWD, line selector LWD, subscriber N5. In the same way as in a connection between a subscriber of the exchange set C with a subscriber of the exchange set B, the sender S1 by means of time switches arranged in the transferrer UEB1 is stimulated to send out high frequency impulses over the line L1 to the operator at definite time intervals. These impulses are taken up by the receiver E1 in the principal exchange and connect a signal lamp Z1 in normal manner.

If a subscriber of the sub-exchange E wishes to make a connection with a subscriber of the same exchanges, then after the subscriber N6 has initiated a connection and a connecting path to the operator: subscriber N6, call finder ASE, transferrer UEE, secondary line switch MWE, connecting line L6, call finder ASC in the exchange C, transferrer UEC, secondary line switch MWC, connecting line L4, transferrer UEB1, connecting link VAI, connecting line L1, connecting link VA in the principal exchange A, the operator sets the direction selector RWE and the line selector LWE in the sub-exchange by sending out certain impulse series so that the subscriber N7 has called and the speaking connection between the two subscribers in the sub-exchange E is made. The time impulse is now given to the operator's position by means of a sender S4 which is stimulated by the time switch in the transferrer UEE of the sub-exchange E after definite intervals during the connection. The time impulse extends from the sender S4 over the connecting line L6, coupling line c (this line also has frequency filters which only permit the transferring of high frequency impulses) connecting line L4, coupling line b, connecting line L3, to the principal exchange A. The high frequency impulses sent out by the sender S4 extend therefore, from exchange C in exactly the same way over the line L3 to the principal exchange as with internal connections over the exchange C. Since in both exchanges two connections can now exist at the same time the operator must receive different time signals. For this reason the sender S4 sends a time signal with a different frequency to that sent by the sender S3 in the exchange C. By means of the impulses sent out by the sender S4 with a different frequency over the connecting line L3, not the receiver E3 in the principal exchange, but the receiver E4 is influenced so that by it the lamp Z2 is connected corresponding to the time signal. By this lamp, therefore, the time signal is transferred to the operator by internal connections inside the sub-exchange E.

If the subscriber of the sub-exchange E wishes to speak with a subscriber of the exchange C the connection extends as follows after the setting of the selector in the exchange C by the operator: subscriber N6, call finder ASE, transferrer UEE, secondary line switch MWE, connecting line L6, call finder ASC in the exchange C, transferrer UEC, direction selector RWC, line selector LWC, subscriber N3. By this connection the time signal is passed through the sender S3 in the sub-exchange C and this is stimulated at definite time intervals by the time switch arranged in the transferrer UEC. The time impulses extend then from the sender S3 over connecting line L4, coupling line B, connecting line L3, receiver E3 in the principal exchange. By means of the receiver E3 the time signal is trans-

mitted to the operator through the lamp Z3. A connection from a subscriber of the sub-exchange E to a subscriber of the automatic exchange B extends in a similar manner to an already described connection from a subscriber of the exchange C to a subscriber of the exchange B. Time impulses are sent over the line L1 to the receiver E1 in the principal exchange through the sender S1 of the exchange B which sender is stimulated by the time switch provided in the transceiver UEB1 at definite time intervals to send out impulses. By means of the receiver E1 in the principal exchange A the signal lamp Z1 is switched in.

Also in a connection from a subscriber of the sub-exchange E to a subscriber of the sub-exchange D, the sending out of time impulses follows in the same way through the sender S1 working together with the time switch arranged in the transceiver UEB1. When the dial impulses have been sent out by the operator such a connection extends as follows: subscriber N6, call finder ASE in the sub-exchange E, transceiver UEE, secondary line switch MWE, connecting line L6, call finder ASC in the exchange C, transceiver UEC, secondary line switch MWC, connecting line L4, transceiver UEB1 in the exchange B, group selector GW, transceiver UEB2, connecting line L5, secondary line switch MWD of the sub-exchange D, transceiver UED, direction selector RWD, line selector LWD, subscriber N5.

Finally the operations for connections going out from the subscribers of the sub-exchange D should be mentioned. If a subscriber of a sub-exchange D wishes to make a connection with a subscriber of the automatic exchange B then after initiating the connection he reaches the operator by the following path: subscriber N4, call finder ASD, transceiver UED, secondary line switch MWD, connecting line L5, transceiver UEB2, connecting link VA2, connecting line L2, connecting link VA of the principal exchange A. After the setting of the connecting devices by the operator the connection exists as follows: subscriber N4, call finder ASD, transceiver UED, secondary line switch MWD, connecting line L5, transceiver UEB2, group selector GW, line selector LW, subscriber N1. Over this connection the time impulses are transferred to the operator by means of the sender S2 which is stimulated to send out impulses at definite time intervals by means of a time switch arranged in the transceiver UEB2. The time impulses pass from the sender S2 over the connecting line L2 and are taken up by the receiver E2 which connects the signals to the operator by lighting up the signal lamp 2.

If a subscriber of the sub-exchange D wishes to make a connection with a subscriber of the sub-exchange C, this connection after the setting of the connecting devices concerned by means of the operator exists as follows: subscriber N4, call finder ASD in the sub-exchange D, transceiver UED, secondary line switch MWD, connecting line L5, transceiver UEB2, group selector GW, transceiver UEB1, connecting line L4, secondary line switch MWC in the sub-exchange C, transceiver UEC, direction selector RWC, line selector LWC, subscriber N3. By means of this connection as in the preceding the time signal is sent out by the sender S2 to the operator's position and the sender S2 is stimulated to send out impulses at definite time intervals by means of the time switch arranged in the transceiver UEB2.

A connection from a subscriber of the sub-

exchange D to a subscriber of the sub-exchange E extends in similar manner to the connections described above. Also in this connection the time signal is transferred in the same way by means of a sender S2 over the connecting line L2 to the operator.

If several links are present in the same exchange several connections can exist at the same time, or if several connecting lines pass between two exchanges, and between these exchanges several connections can be made at the same time, it is thus not only necessary to have a sender with different frequency for each link but also to acquaint the operator with the manner in which the signal lamps and connections are related. For this purpose the individual links are so made that at the reply of the desired set and withdrawal of the plug the corresponding sender is stimulated to send out a signal impulse. At the operator's position, therefore, after the withdrawal of the plug a lamp immediately lights up so that the operator knows that by means of this lamp the directly made connection is supervised with regard to the conversation length.

For the rest it should be recommended that this starting impulse should be transmitted to the operator every time in order to save her from mental work and avoid error.

In Fig. 2 part of the exchange C is shown in detail, i. e., part surrounded by dotted lines.

After the initiating of the connection by a calling subscriber of this exchange i. e., after the receiver is removed and the crank operated, a call relay AN, not shown, is energized and connects the relay N over: earth, contacts 19an, 20p, winding of the relay N, battery, earth. The relay N operates two contacts 8n and 21n which are so arranged that the contact 8n is closed somewhat before the contact 21n. When the call finder AS stands on the contact on which the calling line is connected the test relay P immediately operates and by opening the contact 20p prevents the call finder from moving any further. If this is not the case, however, by means of contact 21n the circuit for the magnet Da of the call finder is closed: earth, contact 19an, 20p, 21n, 23r, magnet Da, battery, earth. The magnet at Da has a contact 22da after the operation of which relay R is connected over resistance W25. Relay R opens at contact 23r, the circuit indicated above for the magnet Da so that the contact 22da is closed and a short-circuit thus made for the winding of the relay R. The contact 23r is therefore closed after a short while so that the magnet Da of the call finder is again connected. The interplay between the magnet Da and the relay R continues until the call finder has found the calling connecting line and the following circuit is made: earth, wiper d25 in its rest position, contacts 9c, 8n, windings II and I of relay P, wiper da3, lead c, and battery, which is not shown. The relay P operates in this circuit, stops the call finder by opening the contact 20p, locks the calling line by disconnecting its high resistance winding II at the contact 7p, and switches through the speaking leads by closing its contacts 1p and 2p. By the opening of contact 20p the relay N releases. The relay P further closes its contact 45p and connects the lead c2 with battery. In this way the secondary line switch MWC (Fig. 1) is started up and comes to a stop when the leads a2, b2 and c2 have been found. Over connecting line L4 and devices of the sub-exchange B and line L1 the connection to the

operator in the principal exchange A is now made in the known manner. By means of a signal the operator is made aware of the presence of a call while a signal is also transmitted to the calling subscriber over lead *a*2 and the condenser *Co*1 and *Co*2, contacts *5p*, *3k*, *1p*, wiper *da*1. The operator now enters the connection in that she puts the plug in the call jack so that at the same time a battery potential is laid on the lead *a*2 and the relay I operates.

If the calling subscriber has given the calling impulse by turning the crank, without lifting his receiver, the relay Y is not energized, consequently the contact *40y* is open and thus the battery is not connected to the lead *b*2 over contact *39kh*, resistance *Wi*9, (the connection of the battery over *Wi*9 at this moment would connect a signal to the operator from which she would recognize that the calling subscriber is waiting to lift up his receiver). The operator may now call the subscriber desiring the connection. She operates the call key and thus sets the battery to the lead *b*2; in this way the relay E is energized over contact *41y*. By the closing of the contact *106e* the following circuit is made for the relay W: earth, contact *106e*, winding of the relay W, resistance *Wi*8, battery, earth. By closing of the contact *33w* the call machine RM is connected to the line *b* lead to the subscriber by which the calling devices at the subscribers' set is operated. When the subscriber lifts his receiver the following circuit is made: earth, battery, resistance *Wi*4, winding of the relay X, contact *28i*, *4k*, *3k*, *1p*, wiper *da*1, lead *a*, subscriber's loop, lead *b*, wiper *da*2, contacts *2p*, *6k*, *32w*, *36e*, winding of the relay Y, earth. In this circuit the relays X and Y operate. If the subscriber has lifted his receiver during the sending out of the call this circuit cannot be made since the contact *33w* is closed, thus relay X alone operates and by closing its contact *103x* makes a short-circuit for the winding of the relay W. Relay W therefore releases immediately so that by the closing of the contact *32w* the relay Y is also connected. The relay Y closes its contact *40y* and thus lays battery potential over contact *39kh* and resistance *Wi*9 to the lead *b*2 connected to the operator's position. In this way the operator receives a signal which makes her aware of the reply of the subscriber. The relay I has closed a circuit for the relay C by closing its contact *67i*: earth, contact *67i*, winding of relay C, resistance *Wi*11, battery, earth. The relay C closes a holding circuit for itself at contact *55c*. Therefore it makes the energizing circuit for relay P (winding I) independently of the setting of the wiper *da*5 of the time switch.

The operator now makes an inquiry to the subscriber and sends out an impulse series affecting the relay I by which if an internal connection, i. e., the connection with a subscriber of the same exchange is required, the direction selector RWC consisting of an auxiliary selector (with a magnet *De*) and the principal selector (with the magnet *Dh*) is set on the leads *a*3, *b*3, *c*3. The magnet *De* of the auxiliary selector receives impulses of the following path each time the relay I releases: earth, contact *54p1*, *109i*, *114c*, magnet *De*, battery, earth. On the first release of the relay I the following circuit arises for the relays V and VI of which the relay VI has a delayed release and holds during the impulse series: earth, contacts *66i*, *65c*, winding of the relay V, parallel winding of the relay VI, battery and earth. Magnet *De* and the auxiliary

- selector has a contact *43de* by means of which the relay H is connected: earth, contact *43de*, winding of the relay H, battery, earth. At the end of the first impulse and repeated energizing of relay I the following circuit for the relay K is made: earth, contacts *73i*, *72h*, winding of the relay K, battery, earth. Relay K opens its contacts *3k*, *4k*, *6k*, whereby the speaking leads are interrupted and relays X and Y are released.
- 10 After the release of the relay Y the following holding circuit for the relay K is closed: earth, contact *69c*, wiper *de2*, the first two contacts set on one another (setting of *De* on these contacts only by local subscribers), winding I of the relay *Kh*, contacts *70k*, *71y*, winding of the relay K, battery, earth. In this circuit the relay *Kh* also operates.
- 15 At the end of the impulse series the relay I remains energized for some time, so that with the contact *66i* remaining open, relay VI as well as relay V is released. After the release of relay VI the following circuit is made for the magnets of the principal selector *Dh*: earth, battery, magnet *Dh*, contacts *113k*, *112v1*, wiper *de3* in its working position, wiper *dh5* in its rest position, contacts *110h*, *54p1*, earth. By means of the contact *44dh* of the magnet *Dh* the relay H is switched in and interrupts the above-mentioned circuit for *Dh* at the contact *110h*. In this way 20 the contact *44dh* is opened again and relay H is released. By the closing of the contact *110h* a circuit for the magnet *Dh* is closed again, now over the following path: earth, contacts *54p1*, *110h*, wiper *dh5* in its operated position, magnet *Dh*, battery, earth. The alternate play between the magnet *Dh* and the relay H continues until a free lead *c*3 has been found and the wiper *dh4* has been set on the contact, over which earth potential is connected by means of wiper *de1* and contact *55c*. Then the following test circuit is made: earth, contact *55c*, wiper *de1* and wiper *dh4* in its fixed position, winding I of the relay *P1*, wiper *dh3*, lead *c*3 and battery. The relay *P1* by closing its contact *59p1* locks itself in the following circuit: earth, battery, winding II of the relay *P1*, contact *50p1*, wipers *dh4* and *de1* in their fixed positions, contact *55c*, earth. By the closing of the contact *48p1* direct earth potential is laid to the lead *c*3 over contact *55c* and thus 30 the subsequently arranged connecting device seized is locked against any other seizing.
- 35 The operator now sends out impulse series to set the following line selectors, by which impulses the relay I is impulsively energized, and which impulses are transferred to the line selector over contact *28i* and the lead *a*3. A further influencing of the magnets *De* and *Dh* is not possible since the contact *54p1* is open. Should the line selector be set on the desired subscriber, calling current is sent out to him in the following manner: by the closing of the contact *53p1* the following circuit is closed for the relay F: earth, contacts *53p1*, *52x*, *51v1*, winding of the relay F, battery, earth. The relay F closes its contact *104f* and thus makes a circuit for the magnet *Dz* of the time switch: earth, contacts *104f*, *99kh*, *102v1*, *103z*, magnet *Dz*, battery, earth. The magnet *Dz* moves its wipers *dz1*—*dz5* forward by one step. At the same time it closes its contact *101dz* and thus the following circuit for the relay Z: earth, contact *101dz*, winding of the relay Z, resistance *Wi*7, battery, earth. The relay Z interrupts at the contact *103z* the circuit for the magnet *Dz*, so that this restores. The 40 following holding circuit is closed for the relay Z:
- 45
- 50
- 55
- 60
- 65
- 70
- 75

earth, battery, resistance W_{17} , winding of the relay Z, contacts 96z, 97th, 99kh, 104f, earth. By the closing of the contact 92z the following circuit is closed for the relay R1: earth, battery, winding of the relay R1, contacts 92z, 115s, 99kh, 104f, earth. The relay R1 closes its contact 100r1 and thus makes a short-circuit for the winding of the relay Z, which releases and also by opening its contact 92z brings the relay R1 to release. The circuit indicated above for the magnet Dz is now closed again by contact 103z, so that a further stepping on of the wiper takes place. The magnet Dz and the relays Z and R1 form an interrupting device by which the wipers of the magnet Dz are stepped on in a stepwise fashion. Each time the wiper dz2 reaches the contacts connected with one another the following circuit is closed for the relay W: earth, wiper dz2, contacts connected with one another, contact 107f, winding of the relay W, resistance W38, battery, earth. The relay W closes its contact 33w and thus lays calling current to the lead b3 leading to the desired subscriber whereby his calling device is operated.

When the called subscriber replies a circuit is made for the relays X and Y over his loop: earth, battery, resistance W_{14} , winding of the relay X, contacts 28i, 41p1, wiper dh1, lead a3, loop over the called subscriber, lead b3, wiper dh2, contacts 48p1, 32w, 36e, winding of the relay Y, earth. If the subscriber has replied directly during the laying on of the calling current only relay X operates, and by closing its contact 108x makes a short-circuit for the relay W and stops the sending out of the calling current, at the contact 32w; on the closing of the contact the relay Y then operates. By the opening of the contact 114y the above mentioned holding circuit for the relay K is opened so that by the closing of the contacts 3k, 4k and 6k the speaking leads are switched through and the conversation between the two subscribers can begin. Relay F is brought to release by the opening of the contact 52x, so that an influencing of the magnet Dz in the described manner can no longer result by the interruptions at the contact 104f.

If at the time of replying of the called subscriber the wiper of the magnet Dz was not in the rest position, then, by the opening of the contact 71y, the relay Kh, which, as has previously been indicated is energized together with the relay K, does not release, since it has closed for itself the following holding circuit: earth, wiper dz3 in its operated position, contact 46kh, winding II of relay Kh, battery, earth. As a result the contact 93kh is closed so that earth is laid to the wiper dz4. As a consequence the following circuit is made for the magnet Dz: earth, battery, magnet Dz, contacts 103z, 102r1, 115s, 91z, wiper dz4 in its operated position, contact 93kh, earth. By the closing of the contact 101dz a previously mentioned circuit for the relay Z is closed, so that by the opening of the contact 103z the above mentioned circuit for the relay Dz is opened. By the opening of the contact 101dz the relay Z is again deprived of current, so that by the closing of the contact 103z the magnet Dz is again switched in. In this way by means of the magnet Dz the wipers of the time switch are stepped on, and actually more quickly than previously since the relay R1 does not now come in. The play between the magnet Dz and the relay Z continues until the wipers of the magnet Dz have reached their rest position. Then the holding circuit for the winding II of

the relay Kh is opened at the wipers dz3, so that this releases and among other things opens its contact 93kh and, by disconnection of earth potential from the wiper dz4 a further influencing of Dz is prevented. The relay Kh has further closed its contact 39kh. In this way, over contacts 40y, 39kh and resistance W_{19} , battery potential is laid to the lead b2 leading to the operator's position, and hence a signal is connected at the working position from which the operator recognizes that the speaking connection between the subscribers is made. Hence she withdraws the plug from the jack, so that the relay I is brought to release. Thus the relays V and VI operate again over contacts 66i and 65c. Then the following circuit arises for the relay S: earth, contacts 26p1, 25y, 24v, winding of the relay S, battery, earth.

The conversation metering now begins, for which the switch mechanism Dz is used again. After the operation of the relay S the following circuit is made for the magnet Dz: earth, contacts 69c, 94s, 91th, 102r1, 103z, magnet Dz, battery, earth. The switch mechanism Dz thus switches its wiper to the first contact. At the contact 101dz the relay Z is again connected, and interrupts the circuit indicated above for Dz at the contact 103z. The opening of the contact 101dz does not bring about, however, the release of the relay Z, since this has in the meanwhile locked itself in the following circuit: earth, battery, resistance W_{17} , winding of the relay Z, contacts 96z, 94s, 69c, earth. At the same time the contact 68z is closed and thus a thermo-relay Th is heated. After some time the contact 98th is closed, whereby a short circuit is made for the winding of the relay Z over contact 98th. The relay Z thus releases and opens the circuit for the thermo-relay at the contact 68z. After a definite cooling off period the contact 91th is closed again and thus the circuit mentioned above for the magnet Dz is closed again. The resistance ratio in the above-mentioned switch mechanism is so arranged that the interval between the individual steps should amount to about one minute. The wiper dz1 is therefore brought to the fourth contact when the conversation has lasted 3 minutes. The following circuit then exists for the relay AR: earth, contact 74s, wiper dz1 on contact 4, contact 75hr, of an auxiliary relay HR, winding of the relay AR, battery, earth. By the closing of the contact 18ar there follows the laying of earth potential to the lead going to the sender S3 for the first time. The sender is induced for the first time to send a high frequency impulse over the connecting leads L1 and L3 (Fig. 1) to the operator's position in the principal exchange, which is taken up by the receiver E3 and the signal lamp Z3 thus switched in. The operator recognizes that the internal conversation in the exchange C has lasted more than the 3-minute limit. She notes it down on the conversation form which is in the compartment corresponding to the lamp Z3.

The laying of earth to the lead passing to the sender S3 through contact 18ar lasts only for a short time. On the energizing of the relay AR the contact 71ar and thus the following circuit for the auxiliary relay HR is also closed: earth, contact 14s, wiper dz1 on contact 4, contact 71ar, winding of the relay HR, battery, earth. The relay HR locks itself in a holding circuit so long as the wiper dz1 rests on the contact 4 (i. e., one minute), by closing its contact 76hr. By the opening of the contact 75hr the energizing cir-

cuit for the relay AR is opened and thus at contact 18ar the impulse for the sender S3 is completed.

The same operations take place when after 3 minutes the wiper d21 reaches the contact 7 and after further time intervals the contacts 10 and 13. The operator thus receives the time signal at intervals of 3 minutes and can thus note the duration of the conversation and subsequently determine the fee for the conversation on the reckoning form.

By different wiring in the contact bank of the time switch it is naturally possible without further addition, to alter the time periods and to adapt them to the existing scale of charges. For example, if a time fee is due for the first three minutes and the further fees are adjusted from minute to minute, then from contact 4 onwards all contacts must be wired. It must be insured in some way or other that relay HR can release at each step. The sender S3 is therefore stimulated to send out impulses each minute from step 4 of the time switch onwards. If for reasons given earlier it is necessary to send out impulses immediately after the reply of the called subscriber, in order for the purpose of eliminating cases of doubt to indicate at once to the operator the signal lamp, which allows her to supervise the time of the connection which has just been made, then the contact 1 of the contact bank of the time switch must also be wired, so that immediately after the stepping on of the wiper d21 to the first contact there results a sending out of impulses to the operator.

Also a forced separation of the connection is arranged after the lapse of a certain period, namely if the wipers d25 have reached the contact 13, i. e., the conversation has lasted 12 minutes, a short circuit is made for the relay Y so that it releases. The release of the relay Y initiates the release, which then occurs if before the expiration of the 12 minutes the connected subscriber gives the clearing signal. On the release of the relay Y the contact 25y opens the circuit for the relay S which immediately releases. By the closing of the contact 58s a short-circuit for the winding of the relay C is formed over the contact 57v still closed, so that this restores. It opens its contact 10c over which the relay P would be maintained energized on the stepping of the wiper d25 from its rest position, so that now the relay P is brought to release. By the opening of the contact 55c the holding circuit for the relay P1 is also opened so that this releases. For the magnet Dh the following circuit is closed: earth, contact 54p1, 110h, wiper dh5 in its operated position, magnet Dh, battery, earth. The magnet Dh operates its contact 44dh and thus closes a circuit for the relay H, which operates and at the contact 110h interrupts the circuit indicated above for Dh. By opening the contact 44dh the relay H is disconnected, so that by the closing of the contact 110h the magnet Dh is energized again. In this way the wipers of Dh are stepped on to their rest position. Then the following circuit exists for the magnet De: earth, contacts 54p1, 110h, wiper dh5 in its rest position, wiper d23 in its operated position, contact 111c, magnet De, battery, earth. Also this magnet with the aid of its contact 43de acts together with the relay H as an interrupter and switches its wipers to the rest position. Then the following circuit is made for the magnet Dz: earth, contacts 54p1, 7

110h, wipers dh5, d23, both in their rest position, wiper d24 in its operated position, contacts 91z, 115s, 10271, 1032, magnet Dz, battery, earth. The magnet Dz with the aid of its contact 101dz and the relay Z, as already mentioned many times, acts as interrupter and also brings its wipers to their rest position. Thus all devices have been set in their rest positions.

If a subscriber of the sub-exchange C wishes to speak with a subscriber of the sub-exchange E the operations correspond to those for local connections up to the point where the operator comes into the connection; corresponding to the desired traffic direction the operator now sends out other impulse series, whereby the auxiliary selector De is set in another manner and actually the wiper d22 sets itself on the last two contacts to which the resistance W10 is connected. The principal selector Dh sets itself then on the direction given by the auxiliary selector De, so that the wipers dh1-dh3 are set on the leads a4, b4, c4, and thus on the connecting lines L6. The operator by sending out further impulse series sets the connecting devices of the sub-exchange E in such a manner that the desired subscriber N7 is reached over the line selector LWE (Fig. 1).

When the required subscriber replies, the relays X and Y operate in the manner described and in the same way as already described there begins the transferring of the time signal to the operator's position, in that the time switch Dz of the exchange C dispatches impulses to the sender at definite conversation time intervals, which brings about the connection of the signal lamp Z3 at the operator's position by sending out high frequency impulses over the connecting lines L4 and L3.

The release of the connection follows in manner already described.

A difference in the method of working to that in the previously described exchange connection consists only in that the relay Kh causing the call sending at the contact 93kh remains uninfluenced, since in this case the sending out of calling current is controlled by devices of the required exchange.

As previously described connections from a subscriber of the sub-exchange E to a subscriber of the sub-exchange C are supervised as regards time by the time switch in the exchange C.

In such connections the calling subscriber N6 reaches over the call finder ASE, the transfer UEE, the secondary line switch MWE, connecting line L6 to the call finder ASC of the sub-exchange C, where the call relay AN, not shown, operates and closes its contact 19an. The call finder is stepped on in the described manner until it has been set on the leads a1, b1, c1.

Calling of the operator, building of the connection, calling of the required subscriber, etc., results in the manner already described. The direction selector RWC is set in the same way as described for local connections, i. e., the wiper d22 of the auxiliary selector is brought to a contact on which the winding I of the relay Kh is connected.

The making of the conversation connection results in the manner already described, as also the indicating of the time signal to the operator in the main exchange and the release of the connecting path.

Should the requirement be satisfied that on internal connections no supervision as regards time be undertaken but only on connections be-

tween subscribers of different exchanges, devices must be provided which differentiate between internal connections and prevent the sending out of time signals to the operator at the main exchange in the case of internal connections.

In Fig. 2a such an additional arrangement is shown. In addition to the devices represented in Fig. 2 an additional wiper *da4* of the call finder ASC is here necessary and *de4* of the auxiliary selector *De*. These two wipers are situated with their specially wired contact banks between the contact *15hr* and the impulse relay *AR*. A circuit for the relay *AR* can only be made with a definite setting of the wipers *da4* and *de4*.

For internal connections, therefore, inside the exchange *C*, the wipers *da4* may rest, for example, on one of the contacts 1 or 2. For the impulse relay *AR* no circuit can be made, so that the sending out of time signals is suppressed.

If a subscriber of the exchange *E* calls a subscriber of the exchange *C*, the wiper *da4* of the call finder ASC stands on the contact 5 which by the action of the wiper *de4* stands in direct connection with the impulse relay *AR*. Therefore, the sending out of time signals takes place.

If a subscriber of the exchange *C* calls and if he is connected with a subscriber of the exchange *E*, the wiper *da4* rests on the contact 3 and the wiper *de4* on one of the contacts 3 or 4. Over these contact settings an influencing of the impulse relay is possible so that with such a connection also a time signalling is undertaken.

What is claimed is:

1. In a measured service telephone system, a local exchange, a calling subscriber's line and a called subscriber's line each terminating at said exchange, a local connection in said exchange joining said two lines for conversation, a distant exchange, an inter-exchange connection between said distant exchange and said local exchange, and means in said distant exchange operated variably over said inter-exchange connection in dependence upon the length of time said local connection is maintained in said local exchange.

2. In a measured service telephone system, a first exchange, a second exchange, an inter-exchange connection between the exchanges, a pair of subscribers' lines terminating at the first exchange, a local connection in the first exchange joining said lines for conversation, and timing means in said first exchange operated to transmit to said second exchange over said inter-exchange connection a timing signal for each unit period of time that said local connection is maintained.

3. In a measured service telephone system, a first exchange, a second exchange, a calling subscriber's line terminating at the first exchange, a called subscriber's line terminating at the second exchange, means for completing a connection between said lines, a third exchange not included in said connection, an auxiliary connection between said third exchange and one of said first two exchanges, and means in said third exchange controlled over said auxiliary connection in accordance with the length of time that said connection between the subscribers' lines is maintained.

4. In a measured service telephone system, a first exchange, a second exchange, a calling subscriber's line terminating at the first exchange, a called subscriber's line terminating at the second exchange, means operated to complete a connection between said lines, a third exchange not

included in said connection, an auxiliary connection between said third exchange and one of said first two exchanges, and timing means associated with said connection between the subscribers' lines effective to transmit to said third exchange over said auxiliary connection a timing signal for each unit period of time that said connection between the subscribers' lines is maintained.

5. In a telephone system, two exchanges, subscribers' lines terminating at the first exchange, an operator's position at the second exchange, means controlled over a calling one of said subscribers' lines for extending a connection to said operator's position, means controlled by the operator at said position for completing a connection local to said first exchange between said calling line and the line of a called one of said subscribers, and timing means associated with said local connection thereafter operated to transmit to said operator's position a timing signal for each unit period of time that said local connection is maintained.

6. In a telephone system, three exchanges interconnected by trunk lines, a calling subscriber's line terminating at the first exchange, a called subscriber's line terminating at the second exchange, an operator's position in the third exchange, means controlled over certain of said trunk lines by the operator at said position for completing between the lines of said subscribers a connection which does not pass through said third exchange, and timing means associated with said connection for transmitting to said operator's position over certain of said trunk lines a timing signal for each unit of time that said connection is maintained.

7. In a telephone system, two exchanges, an operator's position at the first exchange, subscribers' lines terminating at the second exchange, an inter-exchange trunk line, a plurality of link circuits in the second exchange each controlled by the operator at said position over said trunk line to complete a local connection between the lines of a calling one of said subscribers and a called one of said subscribers, and timing means individual to each of said links for causing a timing signal characteristic of that link to be transmitted to said operator's position over said trunk line for each unit period of time that the connection over that link is maintained.

8. In a telephone system, two exchanges, a calling subscriber's line terminating at the first exchange, an operator's position at the second exchange, means controlled over said calling line at times for extending a connection to said operator's position, means controlled by the operator at said position for completing at different ones of said times from the line of said subscriber talking connections of different classes which do not pass through or terminate in said second exchange, and timing means associated with each of said talking connections for transmitting to said operator's position, for each unit period of time that the connection is maintained, a signal characteristic of the class of said connection.

9. A telephone system as claimed in claim 8, having a plurality of inter-exchange trunk lines terminating at the second exchange, and wherein the signals corresponding to different classes of connections are transmitted to the operator at the second exchange over different ones of said trunk lines.

EDUARD WOCHINGER.
